M. H. SPIELMAN.
ADJUSTABLE SUPPORTING MEMBER,
APPLICATION FILED DEC. 18, 1916.
1,261,453.

Patented Apr. 2, 1918.

UNITED STATES PATENT OFFICE.

MILTON H. SPIELMAN, OF CLEVELAND, OHIO, ASSIGNOR TO THE DOMESTIC ELECTRICAL COMPANY, OF CLEVELAND, OHIO, A CORPORATION OF OHIO

ADJUSTABLE SUPPORTING MEMBER.

1,261,453.

Specification of Letters Patent. Patented Apr. 2, 1918.

Application filed December 18, 1916. Serial No. 187,511.

To all whom it may concern:

Be it known that I, MILTON H. SPIELMAN, a citizen of the United States, residing at Cleveland, in the county of Cuyahoga and State of Ohio, have invented a certain new and useful Improvement in Adjustable Supporting Members, of which the following is a full, clear, and exact description, reference being had to the accompanying drawings.

This invention relates particularly to means for adjusting the nozzle of a vacuum cleaner by raising and lowering the same with relation to the surface operated upon. It is common practice in the manufacture of vacuum cleaners to provide separated axially aligned supporting rollers or wheels adjacent the nozzle of the suction cleaner, and provide one or more supporting wheels positioned rearwardly of the nozzle and its supporting wheels. In order to raise and lower the spout with relation to the carpet or the rug, means are provided for relatively adjusting the height of the axis of the rear or front wheels.

An object of this invention is to provide a simple effective means for adjusting the axis of one of the supports for such a device, which shall be positive in its operation and which may be cheaply manufactured. More specific objects are to make the adjusting device quickly and easily operable to secure the desired adjustment, and to so construct the same that it may be very securely held in any position given it with relation to the device supported.

The above and other objects will become apparent in the following description which refers to the drawings. The essential characteristics of my invention are summarized in the claims.

Referring to the drawings, Figure 1 is a side elevation of a suction cleaner illustrating the application of my invention; Fig. 2 is an enlarged side elevation of the adjusting device; Fig. 3 is an edge elevation of the same; Fig. 4 is a vertical section taken on a plane just inside of the parts comprising

my adjusting device and looking outwardly; Fig. 5 is a vertical axial section taken on the plane indicated by the line 5-5 of Fig. 2.

Designating the parts by reference characters, A indicates the motor housing, B the fan chamber, C the intake nozzle and D the discharge spout of a suction cleaner which may be of any type. E indicates the usual bail for the handle F, the bail being shown as pivoted at opposite sides of the motor housing, and at G is indicated the usual dust bag. The nozzle C, fan casing B and discharge spout D are usually so connected together as to form a rigid frame which is supported adjacent the intake nozzle on axially separated wheels H, mounted on an axle member K suitably connected to the cleaner frame. Rearwardly of the wheels H and preferably positioned to run between the paths of the wheels H is a wheel 10. This wheel may be mounted on a caster support or rigidly held, as desired. To raise and lower the intake nozzle with relation to the surface operated upon (indicated by the line L) it is customary to provide means for vertically adjusting the axis of the wheels H or the wheel 10.

My invention is concerned with novel mechanism for raising and lowering the rear portion of the frame of the cleaner by acting upon the supporting member connecting the wheel 10 with the frame.

The particular method for accomplishing this adjustment and shown as embodying my invention will now be described. The wheel 10 has its bearing pin 11 carried in a bifurcated end of a downwardly extending arm 12, the arm 12 shown as comprising a straight flat strip 13 and a similar strip 14 extending downwardly at the outer and inner side of the wheel respectively, this strip 14 extending across and being secured to the strip 11 extending upwardly to a pivot screw 15 rigid in a laterally extending boss 20 preferably formed integral with the discharge spout D. The arm 12 embraces a cylindrical shoulder 16 on the screw 15.

- which is slightly enlarged over the shank of the screw, and a suitable head 18 is formed on the screw provides a shoulder, preventing outward movement of the arm with relation to the screw.
- An operating disk 25 is shown as having a hub 26 embracing a bearing 27 of a stud having a shank 28 threaded into the boss 20. The stud 28 is shown as having an enlarged shoulder at 29 form an abutment for the hub 26 while a screw 30, threaded into the outer end of the stud, serves to hold the disk in position, while permitting its rotation.
- The disk 25 is shown as having a curved slot 35 extending from a point adjacent its central pivot and terminating adjacent the periphery of the disk, providing a double cam surface, preferably gradually sloping at all points. At the end of the arm 12 is provided an outwardly extending cylindrical stud 36 closely fitting this slot and so positioned on the arm that upward pressure on the wheel 10 transmits its force to the side of the slot in a direction substantially radially of the disk. This feature serves to transmit the force directly to the pivot stud best using the strength of the materials.
- The periphery of the disk 25 is turned inwardly forming a flange 40, shown as knurled to provide a suitable gripping surface and having scallops or notches 42 at its inner edge adapted to be engaged by a projection 43 on a spring 45 shown as bearing against the face of the boss 20 and looping around the pivot stud and secured tightly against the boss by the shoulder 16 of the screw 15.
- The operation of my device is as follows: When it is desired to raise or lower the intake nozzle C with relation to the surface operated upon, the disk 25 is rotated by gripping the knurled surface with the hand, which moves the stud 36 toward or away from the center of the disk, swinging the arm 12 downwardly or upwardly with relation to the cleaner frame, thereby slightly tipping the frame about the axis of the wheels H.
- The spring 45 with its projection 43, snapping into one of the notches of the flange of the disk, securely prevents it turning and securely holds the wheel 10 in the position given it with relation to the frame. The curve of the groove 35 is such that the gradual cam surface is presented to the stud 36, and however great the pressure on the wheel 10, there is little or no tendency to turn the disk. The spring offers but comparatively slight resistance to turning the disk by hand.

While I have shown the arm 12 as a rigid arm supporting frame on the wheel, it is to be understood that a swivel could be introduced into this arm, permitting a caster ac-

tion with the wheel 10 without departing from the spirit of my invention.

Having thus described my invention, what I claim is:

1. In a device of the character described, the combination of a member to be supported, a movable member mounted thereon and having a cam surface, an arm pivoted to the member to be supported, a connection between said arm and said cam surface, and means tending to hold said movable member in any position given it.

2. In a device of the character described, the combination of a frame to be supported, a rotatable member having a cam surface extending outwardly with relation to its pivot, an arm pivoted adjacent said rotatable member and having a member engaging said surface, a roller carried by the arm and adapted to bear against the floor, and means bearing against and preventing inadvertent rotation of the rotatable member.

3. In a device of the character described, the combination of a frame to be supported, a wheel forming part of the support of said frame, an arm extending from the wheel to the frame, a lateral extension on said arm, a rotatable disk having a curved slot eccentric with relation to its pivot and embracing said extension whereby turning the disk may move the arm to raise or lower the adjacent portion of the frame, said disk having a laterally turned flange, and a spring bearing against said flange to prevent its rotation.

4. The combination of a frame, an arm supporting the frame at one point and pivoted thereto, a cam for swinging said arm about its pivot, and means for latching said cam in any one of a number of positions the wheel acting as a support in all of said positions.

5. In a device of the character described, the combination of a frame to be supported, an arm pivoted to the frame, a rotatable member having a cam surface, a member coacting with said surface, one of said members being carried by the arm and the other by the frame, and a spring bearing against and preventing rotation of the rotatable member.

6. The combination of a frame to be supported, an arm pivoted thereto, a roller carried by the arm, a rotatable member having a cam surface, a member coacting with such surface, one of said members being carried by the frame and the other by the arm, and means for latching said rotatable member in various positions, whereby the frame may be adjusted to various heights while still supported on said wheel.

7. The combination with a suction cleaner frame having supporting wheels over which the frame may be tilted, of an adjustable supporting device for holding the frame in vari-

ous positions comprising an arm pivoted to the frame, a movable member mounted thereon and having a cam surface, a connection between the arm and said cam surface, and 5 means tending to hold said member in any position given it.

8. The combination with a suction cleaner frame having a supporting wheel over which the frame may be tilted to raise or lower 10 the nozzle, and means for adjusting the

nozzle to various positions comprising another wheel, an arm pivoted to the frame and journaled to said wheel, a rotatable member having a cam surface, a connection between the arm and said cam surface, and a yielding 15 member acting against said cam to hold it in any position given it.

In testimony whereof, I hereunto affix my signature.

MILTON H. SPIELMAN.
